GAME APPARATUS

Joseph F. Benson, Brooklyn, N. Y.

Application May 25, 1933, Serial No. 672,777

11 Claims. (Cl. 273—144)

My present invention relates to a game apparatus and to the playing elements used therewith and aims to provide certain improvements therein.

5 An object of my invention is to provide a chance and game apparatus adapted for use in playing a multiplicity of games with either a given set of playing elements or with different sets of playing elements which may be substituted one for the other at the will of the players. Another object is to provide an apparatus of the character described wherein the playing elements used therewith are adapted to be activated by gravity and which may be rendered controllable by the 10 player or left entirely to chance. Another object is to provide playing elements made up in sets or groups of different colors in any desired proportion or sets of elements provided with notations, indicia or legends thereon corresponding to 15 players, parts or terms used in any game or sport. Preferably these elements will be of spherical form.

The foregoing and various other objects of my invention as well as the construction and operation thereof will be better understood from the detailed description which follows when considered in conjunction with the accompanying drawings which illustrate a preferred embodiment of my invention and wherein:

30 Figure 1 is a front elevation of a game apparatus embodying my invention.

Fig. 2 is a section taken substantially along the planes of the broken line 2—2 of Fig. 1.

Figs. 3, 4, 5 and 6 are sections taken substantially along the planes of the lines 3—3, 4—4, 35 5—5 and 6—6 respectively of Fig. 2.

Figs. 7 and 8 are elevations of groups of different playing elements adapted for use with my game apparatus.

40 Referring to the drawings wherein the same reference characters are employed to designate similar parts in the various figures, the numeral 10 indicates the base of my game apparatus which has side walls 11 and 11a, front walls 12 and 12a and a rear wall 13. Supported by said walls at the top thereof is a hopper or chamber 14 which may be of any desired form and construction and as herein shown is provided with inwardly tapering sides 15 near its bottom and a central partition member 16 which may be removably held within said hopper in any preferred manner.

45 Within said hopper 14 is a secondary chamber 14a formed by an inwardly sloping top wall 14b, a rear wall 14c having an opening 14d therein and side walls 14e. Said chamber 14a is preferably

left without a bottom wall and is provided with a front wall 14f which may be either transparent or opaque as desired depending upon the character of the game which is to be played or the use to which the apparatus is to be put. Pivottally mounted within the chamber and preferably at the rear wall thereof is a pair of transfer members 17 which are pivoted at 17a, said transfer members being slightly spaced apart at their adjacent edges so as to flank the partition wall 16 when used, and having their top faces sloping downwardly toward each other as indicated at 17b. For insuring the movement of the playing elements in the hopper 14 to the bottom thereof so as to be engageable by the transfer members 17 the hopper is formed with an inwardly sloping false bottom 14g.

50 Directly beneath the hopper 14 there is a slide block 18 which is movable between a pair of guides 18a, the front end of said slide block being provided with circular openings 18b and the rear of said slide block having an opening or groove 18c and a pair of upwardly extending pins 18d which project through slots 14h in the bottom of the hopper, said pins engaging the under side of the transfer members 17 and being adapted to move said members 17 upwardly about their pivots 17a as the slide block 18 moves forwardly. For holding the slide block in its rearmost position there is provided a pair of coil springs 18e which are positioned in recesses formed within the slide block, said springs bearing at one end against fixed abutments 19 carried by a partition wall 20. The openings 18b in the slide block are normally disposed directly beneath the open bottom of the secondary chamber 14a. The partition wall 20 at its forward end is formed with spaced circular openings 20a and at its rear end with a slot which underlies the groove 18c and through which projects a finger 21 which is fixedly mounted on a 40 shaft 22. At longitudinally spaced points along said shaft there are provided downwardly protecting fingers 22a, 22b, 22c and 22d, the functions for which will presently appear. If desired the front and top wall of the chamber within which the slide block moves may be provided with transparent windows 20b and 20c so that the playing elements may be seen when moved forward by the slide block.

Below the partition wall 20 is a playing element receiving chamber 23, the bottom of which is provided with a plurality of trap doors 23a, 23b and 23c, each in turn provided with a central upstanding partition wall 24, said trap doors being fixedly mounted upon shafts 25a, 25b and 25c re- 50

spectively to open upwardly, which shafts in turn are rotatable through the medium of links 26a, 26b and 26c respectively, and which links in turn have pins which engage in elongated slots in operating arms 27a, 27b and 27c respectively. The operating arms extend through guide openings in the upper front wall 12a and terminate at their outer ends in enlargements or buttons, 28. At their inner ends the operating arms 27a, 27b and 27c engage in guides 28a carried by the wall 13 and abut against the inturned ends of the fingers 22a, 22b and 22c respectively, as best shown in Fig. 1. For engaging the downwardly extending finger 22d an operating arm 29 is provided. The receiving chamber 23 rearwardly of the trap door 23a is formed with a central partition 24a and is bottomless for a purpose which will presently appear.

Disposed beneath each of the trap doors 23a, 23b and 23c as well as beneath the bottomless portion of the receiving chamber are a plurality of pairs of conduits 30a, 30b, 30c and 30d respectively, the top openings of which underlie and are in alignment with the openings in the bottom of the receiving chamber 23 when the trap doors thereof are open. The lower ends of each of said pairs of conduits 30a, 30b and 30d in turn connect with or are integrally formed with offset pairs of conduits, the lower ends of which latter in turn overlap pairs of grooves or chutes 32 formed in a receptacle 33 which is disposed in inclined relation to the base of the device so that the playing elements when received in said chutes 32 will move by gravity down said chutes until they reach the lower ends thereof or are sooner stopped by a playing element already in said chute. The receptacle may be provided with a transparent cover 33a so as to render visible the playing elements received in the various chutes. The chutes may be suitably designated by letters to differentiate them from each other and the rails of said chutes may also be provided with numbers to indicate the quantity of elements in a chute. The lower end of the duplex conduit 30c is not formed with any offset portion but on the contrary directly overlies a pair of chutes 32a as best shown in Fig. 1. The bottom of the receptacle 33 at its lowermost end is formed with an opening 33b which is normally closed by a slide door 33c which is normally held in closed position by one or more spring detent devices 33d. The slide door 33c extends laterally beyond the sides of the receptacle 33 and is thus provided with a pair of manipulating members 33e.

For receiving the playing elements upon being discharged from the lower ends of the chutes 32 and 32a when the slide door 33c is opened there is provided a downwardly sloping cabinet 34 provided with two superposed chambers 34a and 34b divided by a partition wall 34c, said cabinet being so constructed that the upper chamber 34a connects with one of each of the pairs of chutes 32 and 32a and the lower chamber 34b connects with the other of each pair of said chutes when the slide door is open. The chambers 34a and 34b are provided with deflectors 34f and 34g respectively for directing the playing elements to openings 34d and 34e provided by said deflectors on alternate sides of the center line of said chambers. Disposed rearwardly of the chambers within the cabinet 34 for receiving the playing elements discharged therefrom is a longitudinally partitioned tray 35 which is laterally removable from the cabinet, said tray having end walls 35a formed with openings 35b and 35c which align with the dis-

charged openings 34d and 34e respectively. Adjacent said walls 35a and inwardly thereof the tray is formed with doors 35d and 35e which are laterally slidable into and out of the tray, said doors having openings which are adapted to align with the opening 35c when the doors are in open position. In said position the doors also establish communication between the cabinet 34 and the tray 35 through the openings 35b in the end walls of the tray. If the tray 35 is to be used to transfer the playing elements to the hopper the slide door 35d is opened and the door 35e is closed while receiving said playing elements and the door 35d is closed prior to the tray being removed from the cabinet.

In lieu of manually returning the playing elements to the hopper 14 through the medium of the tray 35 I may provide the apparatus with a conveyor means and thereby preclude the handling of the playing elements by the players and thus insure the initial or proper proportion of playing elements for use in the respective parts of the hopper. To accomplish this both slide doors 35d and 35e are opened and the portion of the cabinet 34 rearwardly of the tray 35 is provided with a middle partition 34h which extends to the rear wall of the apparatus wherat in a vertical rectangular chamber formed by the rear wall 13 and the chamber walls 37, 38 and 39 I affix around a vertical rotatable shaft 40 a helix 30 41 and at the top of the vertical chamber I provide the shaft 40 with means 42 for accommodating an operating handle. At the bottom of the rear wall 13 of the conveyor chamber I provide a pair of spaced openings 13a through which the playing elements from the partitioned chamber 34 will pass into the conveyor chamber. I preferably so dimension the vertical conveyor chamber that the playing elements thus received will be confined to the corners of the chamber at the rear wall of the apparatus as best shown in Fig. 3 and as the helix is rotated said playing elements will be raised to the top of the conveyor cabinet where at said rear wall 13 is formed with openings 13b through which the playing elements will be discharged into the hopper 14 on opposite sides of the partition therein.

In the use of my apparatus, playing elements of any form which will freely slide or roll down an inclined plane may be employed. I prefer, however, to use rounded or spherical bodies and as shown in Fig. 3 it will be apparent that the slide block 18 is designed for such bodies. These spherical elements may be of different colors and/or may have any desired legends or notations thereon and can be used in sets or groups wherein the colored spheres or those having legends thereon may be in varying proportions depending upon the game or use to which the apparatus is to be put. For example, each of the hopper chambers may contain groups of equal numbers of black and white elements, or equal numbers of three or four differently colored elements, or groups containing any arbitrary grouping of colored elements, or grouping of elements with legends or indicia thereon. It will thus be apparent that in lieu of or in addition to coloring the spherical playing elements they may carry or be provided with notations, legends or indicia corresponding to players, parts or terms used in any game or sport.

In Fig. 7 of the drawings I have illustrated a set of six playing elements provided with indicia corresponding to those on the six faces of a die, the particular indicia appearing many times on

the one sphere so as to be visible irrespective of the position which said element occupies. Of course in the use of the apparatus when such elements are employed there will be used any desired multiple of said six elements. In Fig. 8 I have illustrated the application of my invention to playing elements which carry or are provided with indicia or legends corresponding to the values of the playing cards in a deck and although I have shown but six such elements it will be apparent that the number thereof used in the apparatus will correspond in number and legends theron to the number of cards in a deck. With such playing elements too, the particular legend will appear many times on a single sphere.

From the foregoing detailed description it will be apparent that with the game apparatus described and the character of playing elements to be used therewith, various games can be played; for example when using colored spheres a game may involve a race of filling different chutes 32 and 32a with different colored spheres delivered from only one section of the hopper; or where black and white spheres are used various combinations such as white and white, white and black, black and black, etc., can be made the basis of a race, since two playing elements can be simultaneously discharged to a pair of chutes to which said playing elements can be directed and controlled at the whim of the operator who can see the combination of spheres when they are disposed in the openings 18b of the slide block. The possibility of the innumerable games which can be played with elements such as illustrated in Figs. 7 and 8 accordingly become at once apparent; for example, such card games as poker, twenty-one, sixty-six, etc., can be played with the elements of Fig. 8 whereas indicia on the elements of Fig. 7 may be used for any game or in conjunction with some other game where manipulation of a pair of dice in the hands of a player may be considered objectionable. It will also be appreciated that by employing indicia corresponding to the players and terms used in baseball or in golf or any other sport these games can likewise be played with the apparatus.

The operation of the apparatus independently of any game which is to be played thereon is substantially as follows: The hopper 14 on opposite sides of the partition wall 16 or with said partition wall removed is first supplied with the requisite number or sets or groups of playing elements. If the playing elements fill the hopper to a point above the openings 14d in the secondary chamber 14a, elements will find their way into each of the openings 18b. If the elements do not extend up to the openings 14d, the elements will be delivered to said openings by the transfer members 17 when the buttons 28 are pressed inwardly as previously explained. The elements in the openings 18b may be seen through the transparent walls 14f or 20b and 20c, whereupon the player may direct or selectively control the passage of said two playing elements to any of the pairs of chutes 32 and 32a by pressing upon the proper button 28. As any of the buttons 28 which control the operating arms 27a, 27b and 27d are pressed inwardly the corresponding finger 22a, 22b and 22d will be moved rearwardly and turn shaft 22 with which will move arm 21 to engage the slide block 18 and move it forwardly against the tension of the springs 18e to dispose the playing elements over the openings 20a through which they will drop into the receiving chamber 23. But simultaneously with such

action the corresponding trap door controlled by the operating arm will be raised to permit the playing elements to pass through the pair of conduits into a predetermined pair of chutes. Of course when the button 28 upon the operating arm 29 is moved inwardly no trap door is operated but on the contrary the playing elements received within the chamber 23 will pass through the opening in the bottom of said chamber at the rear thereof down through the pair of conduits connecting therewith. It will be understood, that in any selective control employed, the left and right elements in openings 18b will always pass down into the left and right chutes respectively of any pair of chutes. After the desired game has been completed, by moving the slide door 33c outwardly the playing elements from the chutes 32 and 32a will pass into the assorting chambers 34a and 34b and from there either into the receiving tray 35 or through said tray into the rear of the cabinet 34 leading to the spiral conveyor if the slide door 35e is open. From the tray 35 or cabinet 34 the playing elements are returned to the original hopper chamber from which they were discharged as hereinbefore described.

While I have shown and described a preferred embodiment of my invention, the manner in which it is constructed and operable and the playing means with which it is to be used I do not wish to be limited to the details of construction disclosed or to the character of the playing elements illustrated since it will be understood that said parts may be varied without departing from the spirit of my invention.

What I claim is:

1. A game apparatus comprising a hopper for holding playing elements, a plurality of chutes below the hopper for receiving the playing elements and means interposed between the hopper and the chutes for controlling the simultaneous passage of a plurality of playing elements from the hopper into a corresponding number of predetermined chutes.

2. A game apparatus comprising a chamber for playing elements, means for positioning a playing element in a predetermined position within said chamber for release therefrom, a receiving chamber into which the playing element will fall upon being released from the first chamber, a receptacle provided with a plurality of passages leading from the receiving chamber and means for selectively controlling the movement of the playing element from the receiving chamber to a desired passage.

3. A game apparatus comprising a chamber for playing elements, means for positioning a playing element in a predetermined position within said chamber for release therefrom, a receiving chamber into which the playing element will fall upon being released from the first chamber, a receptacle provided with a plurality of passages leading from the receiving chamber and means for releasing a playing element to cause it to pass into the receiving chamber and for causing said playing element to pass from the receiving chamber to a desired passage.

4. A game apparatus comprising a chamber for playing elements, means for positioning a playing element in a predetermined position within said chamber for release therefrom, a receiving chamber into which the playing element will fall upon being released from the first chamber, a receptacle below the receiving chamber provided with a plurality of passages, trap doors in the

receiving chamber overlying the tops of the passages and means for causing a playing element to enter the receiving chamber and for selectively opening a trap door in said chamber for permitting the playing element to enter a predetermined passage.

5. A game apparatus comprising a plurality of chambers, groups of playing elements in said chambers, sets of chutes below said chambers, means for simultaneously releasing an element from each chamber to a predetermined set of chutes, means for discharging the elements from the chutes and means for automatically separating the discharged elements in accordance with 10 their original groupings.

6. A game apparatus comprising a plurality of chambers, groups of playing elements in said chambers, sets of chutes below said chambers, means for simultaneously releasing an element from each chamber to a predetermined set of chutes, means for discharging the elements from the chutes, means for automatically separating the discharged elements in accordance with their original groupings and mechanical means for returning the separated groups of elements to their 20 respective chambers.

7. A game apparatus comprising a pair of chambers, groups or sets of playing elements in said chambers, a plurality of pairs of chutes for receiving the playing elements from said chambers, means for simultaneously releasing a playing element from each chamber, means for selectively predetermining the pair of chutes for receiving the released playing elements, means for 30 discharging the playing elements from the chutes and means for automatically separating the playing elements upon being discharged into two groups according to their original groupings.

8. A game apparatus comprising a pair of chambers, groups or sets of playing elements in said chambers, a plurality of pairs of chutes for receiving the playing elements from said chambers, means for simultaneously releasing a playing element from each chamber, means for selectively predetermining the pair of chutes for receiving the released playing elements, means for discharging the playing elements from the chutes and means for separating the playing elements 10 upon being discharged according to their original groupings and means for returning them to their respective chambers.

9. A game apparatus according to claim 8 wherein the means for returning the separated playing elements to their respective chambers is a mechanically operable conveyor with means for maintaining the playing elements in their separated group relationship while they are being conveyed to their respective chambers.

10. A game apparatus according to claim 8 wherein the means for returning the separated playing elements to their respective chambers is a helical conveyor provided with means for confining the movements of the elements longitudinally of the conveyor.

11. In a game apparatus using gravity activated elements, a feed hopper having a pair of chambers, a pair of chutes for receiving the elements from the respective chambers, a discharge receptacle having a pair of chambers for receiving the elements from the pair of chutes respectively and a mechanical conveyor adapted to carry the elements from the chambers of the discharge receptacle to the respective chambers of the feed hopper from whence they first came.

JOSEPH P. BENSON.
